UNITED STATES PATENT OFFICE.

WILLIAM YELLOWLEY, OF KINGSTON, ONTARIO, CANADA.

MACHINE FOR PAINTING AND DRYING PROJECTILES.

1,153,529.

Specification of Letters Patent. Patented Sept. 14, 1915.

Application filed February 1, 1915. Serial No. 5,597.

To all whom it may concern:

Be it known that I, WILLIAM YELLOWLEY, a subject of the King of Great Britain, residing at No. 69 Union Street, Kingston, Province of Ontario, Canada, have invented certain new and useful Improvements in Machines for Painting and Drying Projectiles; and I do hereby declare that the following is a full, clear, and exact description of the invention, such as will enable others skilled in the art to which it appertains to make and use the same.

The invention to be hereinafter described relates to machines for painting and drying projectiles.

In order to more clearly disclose the construction, operation, and use of the invention, reference should be had to the accompanying drawings forming part of the present application.

Throughout the several figures of the drawings like reference characters designate the same parts.

In the drawings, Figure 1 is a top plan view of my machine cut in half; Fig. 2 is a vertical central section through my machine; Fig. 3 is a side view of one of the idlers supporting the revolving frame; Fig. 4 is a front view of the same; Fig. 5 is a side view of one of the members for holding the shell sockets; Fig. 6 is a front view of the same; and Fig. 7 is a detail of one of the shell sockets.

The main objects of the invention are, to provide a compact, durable, and efficient machine which will enable projectiles to be painted and dried quickly and economically.

Referring to the drawings in detail, 1 designates the circular table which is mounted on suitable legs 2 and provided, at its center, with an integral sleeve 3. Sleeve 3 is in alignment with a central sleeve 4 of a circular frame 5 mounted on top of the table, and a center pin 6 is secured in sleeve 3 of the table and projects a considerable distance from sleeve 4 of the frame, so as to revolvably secure the frame on the table.

The rim 7 of frame 5 has its under and upper faces beveled, the under face being beveled to fit snugly against a friction cone 8 keyed on the inner end of a shaft 9 which is revolvably mounted in a sleeve 10 adapted to be threaded into a journal 11 secured on the table 1. By threading the sleeve 10 into or out of journal 11 the set of cone 8 can be adjusted to suit the set of frame 5. The

outer end of shaft 9 is adapted to be connected to a drive shaft, not shown, so as to rotate the cone 8, which revolves frame 5. Suitable idlers 12, secured to table 1, support the rim of frame 5, as in Fig. 2, so as to insure smooth and easy operation of the same.

A number of equally spaced U members 13 are secured to table 1, around the upper face thereof, concentric with, and a short distance from, the rim of frame 5. A block 14, provided with an integral pin 15 on its upper face, is pivotally mounted in each U frame so as to be easily rocked or swung either inwardly or outwardly. The inner lower corner of the block 14 is rounded so as not to strike the bottom of the U frame 13, and the lower outer portion is given a slight downward slant which engages a slight downward slant of the outer portion of the U frame, so as to positively limit the outward swing of the block (Figs. 5 and 6).

A shell socket 16 is rotatably mounted on the pin 15 and has its upper end screw 80 threaded and adapted to be threaded into the screw threaded socket or recess in the nose of the projectile. This socket 16 is provided with an integral annular collar 17 so positioned that its outer face, which is beveled downwardly and inwardly at the same angle as the upper bevel 7 of the rim of frame 5, will engage the bevel of the said frame when the block 14 and pin 15 are swung inwardly, as shown at the left hand side of Fig. 2.

A U frame 18, provided at its outer end with a bracket 19 adapted to hold the bucket of paint, has its inner arm revolvably mounted on the extended upper portion of pin 6 so as to render the bucket bracket easily revolvable about the machine. This arm 18 is, of course, of such a length that the bucket bracket will not in any way interfere with the projectiles being painted and dried, even when they are swung to their outermost position.

For drying purposes a radiator 20 is centrally located beneath table 1 and the table is surrounded by a concentric sheet metal 105 casing 21 which extends well above the table and is spaced a short distance therefrom.

The projectiles to be painted are placed on the socket 16 and rocked inwardly so as to bring collar 17 of the socket into contact 110 with the upper bevel 7 of frame 5, which is revolved by means of cone 8 as previously

described. The weight of the projectile 22 holds the collar 17 in tight frictional engagement with frame 5 so that the socket 16, and, consequently, the projectile is rotated 5 at a relatively high speed as the frame revolves. The operator, to paint the projectile, dips a brush in the paint carried by bracket 19 and places it against the rotating projectile, moving it from the nose 10 to the heel or bottom thereof, thus painting it quickly and easily. As soon as this operation is complete the projectile is swung outward, and comes to rest in the position shown at the right hand side 15 of Fig. 2, directly over the space between the casing 21 and table 1. The operator walks around the machine, carrying the paint with him by means of arm 18 and bracket 19, repeating the above described operation with 20 each projectile. As he proceeds, the projectiles which have been painted are dried by the current of heated air flowing up between the table and casing 21. When the painted projectile has been dried, which takes place 25 very quickly, it is removed and replaced by an unpainted one and the operation is repeated. By this means large numbers of projectiles can be painted and dried in a very short time.

30 It is thought that the construction, operation, and use of the invention will be clear from the preceding detailed description.

Changes may be made in the construction, arrangement, and disposition of the several 35 parts of the invention without in any way departing from the field and scope of the same, and it is meant to include all such within this application wherein only a preferred form has been disclosed.

40 Having thus fully described my invention, what I claim as new and desire to secure by Letters Patent is:

1. In a machine of the character described, a table, a circular frame revolvably mounted

thereon and provided with an integral rim 45 having beveled under and upper faces, U frames secured to the table concentric with and a slight distance from the rim of said circular frame, blocks pivotally mounted in said U frames and each provided with an 50 integral pin on its upper face and adapted to be swung inwardly or outwardly in the said U frames, a socket adapted to be threaded into the nose of a projectile rotatably mounted on the said pin and provided with an integral annular beveled collar adapted to frictionally engage the bevel on the upper face of the said circular frame when the said block is swung inwardly on its pivot, 55 means for limiting the outward swing of the said block, and drying means.

2. In a machine of the character described, a table, a circular frame revolvably mounted thereon and provided with an integral arm having beveled under and upper faces, U 60 frames secured to the table concentric with and a slight distance from the rim of said circular frame, blocks pivotally mounted in said U frames and each provided with an integral pin on its upper face and adapted 65 to be swung inwardly or outwardly in the said U frames, a socket adapted to be threaded into the nose of a projectile rotatably mounted on the said pin and provided with an integral annular beveled collar adapted 70 to frictionally engage the bevel on the upper face of the said circular frame when the said block is swung inwardly on its pivot, means for limiting the outward swing of the 75 said block, drying means, and means for holding a paint receptacle revolvable about the said table.

In witness whereof I have hereunto set my hand in the presence of two witnesses.

WILLIAM YELLOWLEY.
